US00D955098S

(12) **United States Design Patent** (10) **Patent No.:** **US D955,098 S**
Dunham (45) **Date of Patent:** **** Jun. 21, 2022**

(54) **FOOTWEAR**

(71) Applicant: **Target Brands, Inc.**, Minneapolis, MN
(US)

(72) Inventor: **Austyn Dunham**, Minneapolis, MN
(US)

(73) Assignee: **Target Brands, Inc.**, Minneapolis, MN
(US)

(**) Term: **15 Years**

(21) Appl. No.: **29/754,394**

(22) Filed: **Oct. 9, 2020**

(51) LOC (13) Cl. **02-04**

(52) U.S. Cl.

(57) **CLAIM**

The ornamental design for a footwear, as shown and described.

DESCRIPTION

FIG. 1 is a front, top and right side perspective view of a footwear according to the new design;

FIG. 2 is a front side elevation view thereof;

FIG. 3 is a back side elevation view thereof;

FIG. 4 is a left side elevation view thereof;

FIG. 5 is a right side elevation view thereof;

FIG. 6 is a top plan view thereof;

FIG. 7 is a bottom plan view thereof; and,

FIG. 8 is a back, bottom, and left side perspective view thereof.

The broken lines in the drawings show portions that form no part of the claimed design.

1 Claim, 8 Drawing Sheets
